UNITED STATES PATENT OFFICE

WILLIAM C. NAGL, OF AURORA, OREGON

ELECTRIC SWITCH

Application filed July 29, 1927. Serial No. 209,257.

My invention relates to new and useful improvements in electric switches and more particularly to an electric switch that is especially adapted for use with stop lights for 5 automobiles.

As is well-known to those skilled in the art, many automobiles are equipped with a small signal light in the rear of the machine, the light often being provided with 10 the word "Stop" or with a representation of a hand or some other means, so that when the brake of the automobile is applied, the stop light or signal light will flash and thus warn the drivers of the oncoming machines.

15 The electric switch is connected in a convenient manner to the brake pedal or to the clutch pedal, the idea being that the moment the brake pedal is depressed or the clutch pedal released, the electric switch will immediately function and will continue to function throughout the pressure on the brake or clutch pedal, only to release when the pressure is removed.

It is therefore necessary that some arrangement be provided wherein the switch will immediately make proper contact on pressure of the foot pedal and that the contact remain throughout the entire movement of the pedal, so certain means must be 20 provided that will allow for the entire throw of the brake pedal, and still retain the contact.

25 Still another object of the invention is to provide a switch wherein a rolling and wiping contact is made so that there will be no possibility of the several contacts corroding, which is often the case with the switches now in use.

Still another object of the invention is to 30 provide a small electrical switch for stop light signals wherein an arm is to be mechanically attached to the brake pedal so that the moment it is depressed a rolling electrical contact is made between the two members while a further depression of the 35 pedal will cause one of the contacts to slide or wipe the other contact, while still a further depression will cause the actuated contact to again have a rolling motion, thus 40 assuring a good mechanical contact as well

as electrical contact, and at the same time further assuring a clean non-corroded contact at all times.

Still another object of the invention is to provide a small electrical switch formed 55 of metal wherein certain parts are insulated from others so that a part of the switch may be in the ground circuit and the other part of the switch may be connected directly to the battery as is common in the electric 60 wiring of automobile circuits.

Still another object of the invention is to provide a small electrical switch that is easy 65 to construct, neat in appearance and relatively cheap to manufacturers.

With these and other objects in view, the invention consists of new and novel arrangements and a combination of parts as will be hereinafter more fully described and pointed out in claims.

Referring now to the drawings showing a preferred embodiment of my invention:

Figure 1 is a side-elevation showing the switch attached to a metal support,

Figure 2 is an end view of the same,

Figure 3 is a view similar to Figure 1 but taken from the opposite side,

Figure 4 is an end view similar to Figure 2 but taken from the opposite end, and the switch open,

Figure 5 is a top-plan view, showing the switch attached to a wooden support,

Figure 6 is a fragmentary view showing the moveable contact arm in its early stage of movement,

Figure 7 is a similar view with moveable arm in a more advanced stage of movement, and

Figure 8 is a similar view showing the final position of the movable arm.

Referring now more specifically to the several views, there is shown a small metal casing, having the side 1, the bottom portion 2, and the upwardly extending other side 3 which is in the form of a supporting lip; 5 as may also be seen there are small extensions 4 at the ends of the casings so that bolts 5 may be provided to fasten the casing to the support 6. If the support 6 is wood, no insulation between the casing 1 and the 10

support 6 is necessary but should the casing be fastened to a metal support as shown in some of the figures, a strip of insulation 7 is provided and the small insulating washers 8 may be used under the bolts 5.

There is also small lug or lip 9 formed on one of the extensions 4 so that a spring 10 may be fastened thereto and also fastened to the main operating arm or lever 11, as 10 may be seen in Figure 1.

Near the upper end of this arm 11 is a small link 12, which is preferably formed of hard rubber or any other dielectric, there being small holes 13 in the arm 11 15 so that a small pin 14 may pass thru one of these holes and on which pin will be placed or secured the small link. In other words the link may be fastened within certain limits on the upper end of the arm to allow 20 for the throw of the arm 11 and the brake pedal (not shown). The little link is provided with hole 15 at the outer end so that a cable or a wire (not shown) may be used to connect this link to the brake 25 pedal.

The lower end of the actuating arm 11 is in the form of a hub 16 and is designed to pass thru the one side of the casing and also extend thru the other side of lip 3 as may 30 be seen in Figure 2.

An operation therefore of the arm 11 will cause the small hub 16 to oscillate or partly rotate. On this hub 16 is a small collar 17 which collar is provided intermediate of its 35 length with a small projection 18.

This collar may be sweated or otherwise secured on the hub 16 and is slightly larger in cross section than the small openings in the side and lip, so that after the hub and 40 collar is fitted within the casing and the lip 3 bent in place, there will be no lateral movement of the hub and collar when the arm 11 is actuated.

Supported over the small lip or ear 18 45 is a small curved contact arm or contact member 19, the upper end 20 being struck from a slightly different center while the lower end has the over lapped sides 21 so that a small shaft or pintle 22 may pass thru these overlapping sides 21, the pintle 50 in turn being supported in the heretofore-mentioned ear 18.

The entire actuating contact arm 19 may be cut from a single piece of brass, or other 55 desired metal, the sides 21 being pressed inwardly as shown in the drawing so that the arm will be of sufficient strength to withstand the usage that it is put to.

Secured to the collar 17 is a small spring 60 23 while the other end of the spring is compressed against the inner surface of the arm 19, as may be seen in several views.

Referring now for the moment to Fig. 3, it will be seen that from the upper edge of 65 the side 1 of the casing, there is provided

the integral top 24 which is formed by simply bending over a piece of the sheet metal of which the casing is formed. Also, there are two small integral outstanding ears 25 to limit the throw of the arm 11 in either direction.

Beneath the top 24 there is placed an insulating strip 26 and fastened to this insulating strip is a slightly yieldable or flexible metal strip 27 that is provided with 75 a downwardly extending contact arm 28. This contacting arm is preferably formed of brass, as brass is a good electric conductor. As may be seen in Fig. 3 when the actuating or moveable contact arm 19 is in 80 its rearwardmost position, there will be a slight space between the contact portion 28 and the actuated arm 19.

In other words when the lever or arm 11 is in its normal position the switch will be 85 open.

As also may be seen in the several figures, there is a binding post 29 passing thru the strip 27, the insulation 26, and the top 24, while a small insulating washer 30 is provided 90 so that a wire may be secured to this binding post 29, thus, to conduct the current to the contacting arm 28, but at the same time insulating the current from the casing.

Care should be taken when inserting the binding post that it does not touch the metal of the top 24 and holes larger than the diameter of the post will be provided so that this binding post will not touch the metal 100 of the casing.

A retaining bolt 31 is also properly insulated from the top to help support the strip 27, and its integral arm 28.

Near one end of the top is a binding post 33 which is fastened directly to the top but it will be noticed that this is not insulated 105 from the casing, as the casing itself forms part of the circuit.

Although lead-wires are not shown, it will be understood that a wire will be connected from the binding post 29 to the battery, and a wire will lead from the binding post 33 to the signal light (not shown) while the frame carries the current from the signal light to the battery so that when the actuating arm 19 contacts with the arm 28 the circuit will be completed to thus light the signal light.

Of course the switch might be wired up in some other convenient manner, the idea being as soon as the two contacts are together the circuit of the signal light will be completed.

The operation of the device is as follows: Supposing the small link 12 is connected to the foot pedal and the switch is properly wired, a depression of the pedal will cause the actuating arm 11 to start in its movement and as soon as the hub 16 is actuated or in other words slightly revolved the arm 130

19 will revolve from the position shown in Fig. 3 to the position shown in Fig. 6, thus completing the electrical circuit, and immediately lighting the signal (not shown). A continued movement of the arm and rotation of the hub will cause the arm 19 to compress the small spring 23 while still in contact with the arm 28 to move downwardly as shown in Fig. 7, thus wiping along the inner-surface of the arm 28. The small spring continues to be depressed but after the ears 21 pass the horizontal line drawn thru the axis of the hub, the lower end of arm 19 will pull away from the arm 28 but the pressure of the small spring will cause the upper end 20 of the arm 19 to roll into contact with the arm 28.

When the pressure on the foot pedal is reduced so that spring 10 can return the main actuating arm 11 back to its normal position, of course the movement of the small actuating arm 19 is just reversed from what it was on its former movement, that is, on the start of the return movement of the arm 11 the upper end 20 of the actuating arm 19 will start to roll or revolve away from the arm 28, but as the upper end rolls away the central portion of the arm moves upwardly and wipes along the arm 28 and finally as the small ears pass above the horizontal line thru the axis of the hub the lower end of the arm will revolve away from the arm 28 and finally move entirely away therefrom as shown in Fig. 3.

From this it will be seen that there is first a rolling contact, then a wiping contact and again a rolling contact, both on the actuating of the device and on its return movement, contact being of course kept throughout the three motions.

From this it will be seen that I have provided a switch that will operate instantly on the actuation of the arm 11 by the foot pedal and that the contact will be kept throughout the continued movement of the arm 11 and also thru its return until it has returned to its normal position which is limited by one of the small ears 25.

It will also be seen that due to the rolling and wiping motion, there will be no chance for any corrosion on the arm 28 or the arm 19, thus assuring a good electrical contact at all times throughout the life of the switch.

Although I have described this switch as particularly adaptable for stoplight signals, it will be understood and it is my intention that it may be used in other electrical circuits wherein there is ordinarily a chance of corrosion and where it is desired to provide a switch with a rolling and wiping contact to thus assure clean and bright contacting points at all times.

Again, for the sake of clearness, I have shown the switch just in an open housing,

so that the parts may be readily identified and their operation understood, but in actual practice there will be a further complete shell or covering to keep out any dirt or foreign matter and this shell may also be filled with a very light lubricant, so that all of the moving parts will be well-oiled and operate freely.

I am aware that it is old in the art to provide a switch having a slight rolling and wiping contact but I am not aware of any switch wherein a contact is provided that first rolls, then wipes and then again rolls.

It is obvious that those skilled in the art may vary the details of construction as well as the arrangement of parts without departing from the scope of the above invention.

Having thus described my invention, what I claim as new and desire to secure by Letters Patent, is:

1. An electric switch, comprising a casing, having sides and top, an arm, having a hub extending thru the casing, means for limiting the movement of the said arm in the opposite directions, an insulating link connected to the arm and adapted to be connected to a brake pedal, and a fixed contact member, a pivotally mounted second contact member on said hub, the member on said hub rolling and sliding along the fixed contact member both on the forward and rearward movement of said arm to thereby change the point of contact on both the fixed and moveable members throughout the forward and rearward movements of said arm.

2. An electric switch comprising a relatively flexible stationary member having a contact surface lying in a flat plane, a relatively rigid member mounted for pivotal movement and having a contact surface engageable with the contact surface of the flexible member, the contact surface of the pivoted member having a curved area adapted to initially engage the plane flexible surface of the stationary member and adapted to roll and slide thereon and followed by a plane contact area adapted to slide upon the plane flexible surface of the stationary member.

3. An electric switch comprising a relatively flexible stationary member having a contact surface lying in a flat plane, a relatively rigid member mounted for pivotal movement and having a contact surface engageable with the contact surface of the stationary member, the contact surface of the pivoted member having a curved area adapted to initially engage the flat plane flexible surface of the stationary member and adapted to roll and slide thereon and followed by a plane contact area adapted to slide upon the plane flexible surface, said pivoted member having stiffening flanges

disposed across the line of merger of the curved and plane areas.

4. An electric switch comprising a relatively flexible stationary member having a contact surface lying in a flat plane, a relatively rigid member mounted for pivotal movement upon an axis spaced from the contact surface of the stationary member, said axis being disposed transversely of said surface and lying opposite the same, said pivoted member having a contact surface engageable with the contact surface of the stationary member, the contact surface of the pivoted member having a curved area 10 adapted to initially engage the plane flexible surface and adapted to roll and slide thereon and followed by a flat plane contact area adapted to slide upon the plane flexible surface of the stationary member.
5. In an electric switch, a yieldable stationary contact member and a coacting pivoted contact member mounted to swing at the side of said stationary member and capable of engaging the same with an initial rocking and sliding movement followed 20 with a sliding contact movement over the initial point of engagement and a final sliding movement over said point of engagement.
6. An electric switch comprising a yieldable stationary contact member, a pivot support mounted at a point spaced from the side thereof, a carrier mounted upon the support for turning movement about the axis thereof, a second contact member pivoted upon the carrier at a point eccentric of the axis of the support and a spring interposed between the carrier and the pivoted contact member, the pivoted contact member having a curved surface disposed 30 transversely across the pivot of said contact member and capable of engaging a point upon the yieldable stationary contact with a rocking and sliding movement.
7. A contact member for an electric switch consisting of a body having at its side an engaging surface irregularly and convexly curved from end to end, said member having means for pivotally supporting the same located at a point spaced from the curved surface and lying between the ends thereof.

In testimony whereof I affix my signature.
